(57) **CLAIM**

The ornamental design for an audio component front face, as shown and described.

DESCRIPTION

FIG. 1 is a perspective view of an audio component front face in accordance with our invention;

FIG. 2 is a front elevational view thereof;

FIG. 3 is a side elevational view thereof, viewed from the left side of FIG. 2;

FIG. 4 is a cross-sectional view taken along line 4—4 of FIG. 2; and,

FIG. 5 is a bottom plan view thereof.

The jagged solid line is intended to illustrate the boundary of the claimed design and not part of the design. The broken line showings of the circle in the claimed area, and the remainder of the audio component are for illustrative purposes only and form no part of the claimed invention.
